G. B. CALDWELL,
COMBINATION HAND TOOL.
APPLICATION FILED FEB. 4, 1920.

1,338,420.

Patented Apr. 27, 1920.

UNITED STATES PATENT OFFICE.

GEORGE BYRON CALDWELL, OF OTTAWA, ONTARIO, CANADA.

COMBINATION HAND-TOOL.

1,338,420.

Specification of Letters Patent. Patented Apr. 27, 1920.

Application filed February 4, 1920. Serial No. 356,206.

To all whom it may concern:

Be it known that I, GEORGE BYRON CALDWELL, a citizen of the Dominion of Canada, residing at Ottawa, in the county of Carleton and Province of Ontario, have invented certain new and useful Improvements in Combination Hand-Tools, of which the following is a specification.

This invention relates to improvements in combination hand tools, and has for its primary object to provide an article of the class described wherein a number of tools usually manufactured as separate articles may be combined in a single tool.

A further object is to provide an article of the class described consisting of three tools commonly manufactured as separate tools, and by which invention I provide a combination of these respective tools which will be found convenient for operation and accurate in carrying out that for which they have been designed.

A further object of the invention is to provide an article of the class described whereby a number of tools are combined in the one article of manufacture, which article is so designed that any one of the tools forming the combination will be operative for its own particular use irrespective of the other tools forming the combination.

A further object is to provide an article of the class described consisting in general of a handsaw and the combination therewith of a rule, square, and T-level, the latter being so formed that it will designate the levelness of an article to which either side of the square is placed.

A still further object of the invention is to provide an article of the class described which will be simple and durable in construction, convenient and accurate in use, and economical in manufacture.

With these and other objects in view the invention resides in the novel arrangement and combination of parts hereinafter described in the following specification, illustrated in the accompanying drawing, and set out in the appended claims, it being understood that changes in the precise embod-

iment or embodiments herein described and illustrated may be made within the scope of what is claimed without departing from the spirit of the invention.

In the drawings forming part of this specification and in which like characters of reference designate like parts throughout:

Figure 1 is a side elevation of a saw, part broken away, showing the handle which embodies the several features of my invention;

Fig. 2 shows an enlarged sectional view 60 on the line 2—2 of Fig. 1;

Fig. 3 is a plan view of one of the level retaining plates taken from the inside;

Fig. 4 is a sectional view on the line 4—4 of Fig. 3; and

Fig. 5 is a plan view of the saw blade with the levels in position.

Referring to the drawings, 5 indicates a handsaw having the usual toothed side 6 while its opposite side is provided with a 70 measuring scale 7 of any desired number of units, such as the inch measure, the scale starting from the butt end of the handle as at 8 and extending on one side of the saw blade outwardly from this butt end to the 75 outer end of the blade, while on the opposite side the measuring starts at the outer end and extends toward the butt end.

9 is a handle preferably of wood having a bifurcated butt end as at 10 to receive the 80 saw 5 which is normally held in position by suitable bolts 11. These bolts are preferably four in number so as to keep the saw handle exactly true in relation to its position to the saw blade, the bolts 11 passing 85 through the blade.

Centrally at each side of the handle I provide an annular opening as at 12 in which the wood or other material from which the handle is made is entirely cut out. The 90 saw blade between these openings is provided with a T-shaped opening 14. The upper side of the head of the T as shown at 15 is exactly parallel to the measuring side 7 hereinbefore mentioned, while the 95 side 16 of the upwardly extending portion of the opening 14 is exactly parallel to the butt end 8 of the saw handle. Opposite

these sides 15 and 16 I provide vision notches 17 and 18.

Positioned within the T-shaped opening 14 are two levels 19 and 20 each of which 5 may be embedded in a cylindrical casing 21 if so desired, which casing would have a vision opening as at 22. These spirit levels are positioned centrally in the parts of the T-shaped opening, and two plates 23 and 24 10 are suitably positioned in the openings 12 so as to hold the spirit levels in proper position, the said plates being so formed as to have receiving openings 28 in which the spirit levels 19 and 20 become embedded 15 when the plates are tightened together by the bolts 25, which bolts pass through the saw blade 5.

From the above description and the illustration which I have shown by Fig. 2, it 20 will be seen that the spirit levels are positioned centrally in the blade and thus affords a means whereby the levels will always be true in respect to the said blade. The levels being in such a position are 25 visible from either side.

The handle 9 is provided at the corners of its butt end with plates 26 and 27, the latter having its corner slightly rounded off while the former forms a true square point 30 with the measuring top side of the blade whereby this combination becomes an L-square, both sides of the butt end of the handle 9 having thereon a measuring scale, which scale begins at the opposite end of the 35 butt end on the opposite sides.

This invention is an improvement over my U. S. Patent No. 1,305,587, granted June 3, 1919, and while embodying the basic principle involved in my previous 40 patent this invention contains new novel features for which I respectfully ask that a patent be granted.

From the foregoing it is believed that the advantages of my invention will be 45 readily understood and appreciated, and it is claimed that a convenient combination of a plurality of tools or devices usually manufactured and used as separate articles has been effected in a simple and economical

manner and in a manner to permit of accurate use of each or any of the different articles in the combination.

Having thus described my invention, what I claim as new, is,—

1. An article of the class described, consisting of a saw blade, one side of said saw blade being provided with cutting teeth, the opposite side of said blade having numerals impressed thereon, a handle having its butt end bifurcated, the end of said saw blade being suitably held in said bifurcated end, oppositely registering openings in the respective sides of said handle, a T-shaped opening in said blade between said openings, levels positioned in said T-shaped opening, suitable plates in said openings to hold said levels in said saw blade, the level in the top of the T-shaped opening being parallel to the side of the saw on which said numerals are impressed, the other level being parallel to the butt end of said handle.

2. In an article of the class described, comprising a saw blade, a handle having a bifurcated end to receive said saw blade, 75 means for holding said saw blade in said bifurcated end, the butt end of said handle being at right angles to the top side of said saw blade so as to form a square, said butt end of said handle and said top side of said 80 blade having a tabulated scale thereon, one side numbering outwardly from the meeting point of said scales and the other side numbering towards the meeting point of said scales, openings formed in the respective 85 sides of said handle, a T-shaped opening formed in said blade between said openings, levels positioned in the T-shaped opening, said levels being parallel to the respective measuring sides of said blade and said 90 handle.

In testimony whereof I affix my signature in the presence of two witnesses.

GEORGE BYRON CALDWELL.
